UNITED STATES PATENT OFFICE

149,927

DESIGN FOR A BRACELET OR THE LIKE

Karl C. Augenstein, Cranston, R. I., assignor to Speidel Corporation, Providence, R. I., a corporation of Rhode Island

Application March 7, 1947, Serial No. 137,446

Term of patent 14 years

(Cl. D45—4)

To all whom it may concern:

Be it known that I, Karl C. Augenstein, a citizen of the United States of America, residing at Cranston, county of Providence, and State of Rhode Island, have invented a new, original, and ornamental Design for Bracelet or the like, of which the following is a specification, reference being had to the accompanying drawing, forming a part thereof.

Fig. 1 is a plan view of a bracelet embodying my new design, the links of the bracelet being contracted;

Fig. 2 is a view similar to Fig. 1 but showing the links expanded; and

Fig. 3 is an edge view of a portion of the bracelet.

The dominant feature of my design resides in the link elements which are shown in full lines, with a portion of the bracelet broken away for illustrative purposes only as shown by the center dot and dash lines.

I claim:

The ornamental design for a bracelet or the like, substantially as shown and described.

KARL C. AUGENSTEIN.
